UNITED STATES PATENT OFFICE.

EARL A. THISSELL, OF FLORENCE, MASSACHUSETTS.

VENDING-MACHINE.

SPECIFICATION forming part of Letters Patent No. 530,561, dated December 11, 1894.

Application filed March 30, 1892. Serial No. 427,123. (No model.)

To all whom it may concern:

Be it known that I, EARL A. THISSELL, of Florence, in the county of Hampshire and State of Massachusetts, have invented a new and useful Improvement in Vending-Machines, of which the following is a specification, reference being had to the accompanying drawings, forming part thereof.

My invention relates to automatic machines for vending articles of merchandise and particularly to machines for vending cigars, cigarettes, or other goods contained in packages having substantially the shape of a cigar or cigarette.

15 The objects of the invention are to simplify and cheapen the construction of the coin-controlled mechanism by which access to one or more of the articles is afforded to a purchaser, and to provide means whereby access 20 to any predetermined number of the articles is afforded to the purchaser by the deposit of a single coin, as, for example, three cigars for a twenty-five-cent piece.

To these ends my invention consists in the 25 vending machine constructed and operating as hereinafter fully described and particularly pointed out in the claims.

Referring to the drawings, in which like letters designate like parts in the several views, Figure 1 is a view in perspective of a vending machine embodying my invention. Fig. 2 is a vertical section thereof, taken in the plane of line $x-x$ of Fig. 1. Fig. 3 is a vertical section of the lower end of one of the coin chutes and of one of the goods drawers, and 35 a side elevation of one of the detent levers. Fig. 4 is a plan view of the same parts, the coin chute being shown in cross-section. Fig. 5 is a partial vertical section, taken in the 40 plane of line $y-y$ of Fig. 1.

The letter a designates the case, which is provided with the hinged and locked door a' at the front side thereof and with the locked money drawer a^2 at the bottom and near the 45 rear side thereof. Near the upper end of the door a' are located the slots to receive the coins by which the machine is adapted to be automatically operated, there being, in the example shown, three of such slots of the 50 proper lengths to receive respectively a five-cent piece, a ten-cent piece, and a twenty-five-cent piece, each of said slots being properly

identified by suitable lettering as shown. At its lower end said door is provided with three glass panels a^3 through which the three grades 55 of cigars or other articles are displayed, and preferably has an ornamental mirror panel a^4 located between said transparent panels and said slots as shown. Near the front side of the case is located a removable partition b , extending parallel with the door a' , which partition may be composed of a single piece of wood or other material or may be divided vertically into three equal parts, corresponding in width with the length of the cigars or other 60 articles, as may be desired. The cigars or other articles, being superposed one upon the other, may rest directly against said partition b , but for convenience in placing them within the case I prefer to utilize light trays b' of wood 65 or other suitable material, within which the articles are placed, said trays being adapted to rest against said partition as shown in Fig. 2. Said trays are open at their lower end to permit the articles to descend into the 70 goods drawers, and elastic tapes b^2 are preferably employed to prevent the articles from falling outwardly from the trays when the door a' is opened for any purpose, said tapes being secured at their lower ends to the case 75 and detachably connected at their upper ends to the partition b or to the coin chutes presently to be described. Substantially midway between the bottom of the case and the lower ends of said partition b and the door a' , is located a horizontal partition c , which extends from end to end of the case, and is provided, 80 at the front side of the case, with the open slot c' , which communicates with a shallow trough or receptacle d , located at the bottom 85 of the case, into which the article or articles sold are dropped, and from which they can be readily removed. At the rear side of the case said partition c is provided with the slot or opening c^2 , which communicates with the 90 money drawer a^2 , as clearly shown in Fig. 2. The goods drawers e rest upon said partition c and are capable of a limited sliding movement thereon toward and away from the front 95 side of the case, said drawers, in their normal position, being retained by springs f and the locking devices presently to be described, with their rear ends resting against the rear 100 side of the case and covering the slot or open-

ing c^2 in said partition. Each of said drawers is provided at its front end with a finger-piece e' , extending through the front wall of the case, by which it can be drawn toward 5 said front wall when its locking device is released. The two drawers which are designed to deliver the articles one at a time are each provided with a transverse opening e^2 , extending entirely through the drawer and of a proper width to receive loosely one of the articles to be sold, as shown in Fig. 5, which opening, in the normal position of the drawer, registers with the open bottom of the tray b' above it, whereby the lowermost article is 10 permitted to drop into said opening and to rest upon the partition c . The third drawer, which is designed to deliver a plurality of articles at a time, as for example three cigars, is provided with an opening e^3 , which extends 15 through the drawer in an inclined direction, as shown in Fig. 2, and the drawer is made of a slightly greater thickness, to enable said opening to receive the desired number of the articles, the upper end of said opening registering with its tray, in the normal position of the drawer, in the same manner as the openings of the other two drawers. In the forwardmost position of said drawers the openings therein register with the slot c' in partition c , whereby, when the drawers are moved to such position, the article or articles contained within said openings are permitted to drop through said slot into the receptacle d . 20 The locking and releasing devices for said drawers are constructed as follows:—Projecting from the rear side of the case, above each of said drawers, is a bracket g , upon which is pivotally mounted a locking or detent lever h having at its front end a downwardly projecting hook adapted to engage a locking aperture e^4 in the drawer, when the latter is in its normal position. The rear end of each of said levers is forked, as shown in Fig. 4, the width of the opening thus formed being but slightly less than the diameter of the coin by which the lever is designed to be operated. The front ends of said levers are weighted sufficiently to cause their hooks to normally engage the apertures e^4 in the drawers, as 30 shown in Fig. 2, and yet permit them to be rocked to the position shown in Fig. 5 by the weight of the proper coin, when the latter rests upon the forked rear end thereof. Also supported upon each of said brackets g is a coin chute h , which chutes extend upwardly nearly to the top of the case and are then curved outwardly, through openings in partition b , to the door a' , where their upper ends register with the coin slots in said door. At 35 their lower end said chutes are curved rearwardly to the point where they engage the brackets g , which points are directly above the rear ends of levers h , from which point they extend downwardly in a substantially vertical plane to or nearly to the plane occupied by the rear ends of said levers, when the latter are in their normal position, as shown

in Fig. 2. By thus continuing the lower ends of said chutes below the brackets g , I am enabled to dispense with stops to retain the coin upon the levers h until the goods drawer has been given an initial forward movement, as has heretofore been necessary, the coin, in my device, being retained within the chute itself until such movement is given to said drawer.

The cigars or other articles being placed in position at the front of the case, with the lowermost article occupying the opening e^2 in two of the goods drawers, and the three lower articles occupying the opening e^3 in the third drawer, and door a' and money drawer a^2 being locked, the machine is ready for use. The levers h securely lock the three goods drawers in their rearmost or normal position, so that access either to the goods or to the working parts of the machine is prevented. If now a coin of either of the three denominations mentioned be dropped into its proper slot in door a' , it passes downwardly through the chute leading from said slot to the bottom thereof where it engages the fork at the rear end of the detent lever h beneath said chute, and rocks said lever in a manner to disengage its hook from the goods drawer with which it co-operates. By such movement of the detent lever, its rear end is caused to bear upon the goods drawer, as shown in Fig. 5, the coin still being partly retained within the chute by reason of the downward extension of the latter at its lower end. The purchaser now grasps the proper finger piece e' and pulls the goods drawer outwardly as far as it will go, thereby moving its opening e^2 or e^3 into register with the slot c' in partition c , whereupon the single article or the three articles as the case may be, drops into the receptacle d , the solid portion of said drawer behind the opening therein serving to retain the remaining articles within their tray b' . As the drawer is thus drawn forward its rear end uncovers the slot c' in partition c and permits the detent lever to rock still farther upon its pivot, as represented by broken lines in Fig. 3, and the coin is permitted to escape from the chute and drops into the money drawer. As soon as the purchaser releases his hold upon the finger-piece the spring f returns the goods drawer to its normal position, and the hook of the detent lever again engages the aperture e^4 therein, and the machine is ready to be again operated. Should a coin of less than the proper diameter be dropped into either of the slots it will pass between the arms of the fork on the detent lever without releasing the goods drawer, and if it be of less than the proper weight it will fail to rock the lever, so that all possibility of cheating is prevented.

The vending machine thus described is very simple and inexpensive in construction and yet strong and durable and perfect in operation. It affords to the purchaser three different grades of the articles sold from which to take his choice, and enables him to take ad-

vantage of the customary discount in the price of the article when a number of the same are taken at one time, as, for example, three ten-cent cigars for twenty five cents. The working parts of the machine are effectually protected by the case from dirt and injury, while, at the same time, access thereto when necessary can be readily secured by unlocking the door of the case and removing the partition *b*.

The described construction of the lower ends of the coin chutes and the location thereof relatively to the detent levers specified, insures the release of the goods drawers whenever a proper coin is deposited and obviates all possibility of clogging of the parts.

Having thus fully described my invention, what I claim, and desire to secure by Letters Patent, is—

1. In a vending machine, the combination with a case having a storage space for the articles to be sold and a movable goods drawer adapted to carry said articles from said storage space to the outer side of the case, of a coin chute communicating at its upper end with a slot in the front side of said case which is adapted to receive a coin of a predetermined size, and a locking lever pivotally supported between its ends within said case, said lever having its front end adapted to operatively engage said goods drawer to lock the latter in its closed position and terminating at its rear end in a fork which normally occupies a position adjacent to the lower end of said coin chute, the inside width of said fork being but slightly less than the diameter of the predetermined coin, whereby a coin of less diameter will pass said lever without rocking it, substantially as and for the purpose described.

2. In a vending machine, the combination with the case having the front side thereof composed of a hinged door which is provided with a coin-receiving slot, and having near said front side a removable partition against which the goods are supported in a substantially vertical column, a goods drawer located beneath said partition and movable toward and away from the front side of the case, a pivotally supported detent lever having at its front end a hook adapted to engage a lock-

ing aperture in said drawer and having at its rear end a horizontally disposed fork of slightly less inside width than the diameter of the coin by which it is designed to be operated, a money drawer located beneath the rear end of said goods drawer, access to which is closed by the latter in its retracted position, and a coin chute having its upper end extended through said partition in the case to the coin-receiving slot in the door, said chute terminating at its lower end above the fork on said detent lever and at a distance above the goods drawer less than the diameter of the coin with which it is designed to be used, whereby the coin when dropped through said chute will engage the fork on the detent lever and rock the latter sufficiently to release the goods drawer, but will be prevented from entirely leaving the chute until an initial forward movement is imparted to said drawer, substantially as set forth.

3. In a vending machine, a case provided with a goods storing space and having an open goods receptacle, as *d*, and a horizontally disposed partition, as *c*, having therein a slot or opening, as *c'*, communicating with said receptacle, a plurality of goods drawers resting upon said partition and movable toward and away from the front side of the case, a portion of said drawers having extending therethrough in a vertical plane a transverse opening, as *c''*, and the remainder thereof being provided with a transverse opening, as *c'''*, extending therethrough in an inclined plane, said openings, in the rearmost positions of the drawers, registering with the goods storing space, and, in the forwardmost positions of the drawers, with said slot or opening in said partition, locking devices for said drawers, and coin releasing mechanism therefor, combined and operating substantially as set forth, whereby a portion of said drawers are adapted to deliver the articles one at a time into said open receptacle, and the remainder to deliver a plurality of articles at a time.

EARL A. THISSELL.
